CLAIM

The ornamental design for a case with finger articulation for electronic communications device, as shown and described.

DESCRIPTION

FIG. 1 is a back perspective view of a case with finger articulation for electronic communications device showing a first embodiment of my new design;

FIG. 2 is a back view thereof;

FIG. 3 is a side view thereof;

FIG. 4 is the opposite side view thereof;

FIG. 5 is top view thereof;

FIG. 6 is bottom view thereof;

FIG. 7 is a front view thereof;

FIG. 8 is a back view of a case with finger articulation for electronic communications device showing a second embodiment of my new design;

FIG. 9 is a back perspective view thereof;

FIG. 10 is a back view of a case with finger articulation for electronic communications device showing a third embodiment of my new design;

FIG. 11 is a back perspective view thereof;

FIG. 12 is a back view of a case with finger articulation for electronic communications device showing a fourth embodiment of my new design; and,

FIG. 13 is a back perspective view thereof.

The broken lines depict environmental subject matter that forms no part of the claimed design.
